MUCKING MACHINE

James K. Wilden, Colton, Calif.

Application December 21, 1946, Serial No. 717,699

6 Claims. (Cl. 214—148)

1

This invention relates to mining machinery and is particularly directed to a device for loading ore or rock from a "muck" pile into a mine car. Machines of this type are commonly mounted on rails extending along a mine tunnel and are provided with a power-operated scoop or bucket for raising the ore or rock, and then transferring and depositing it in the mine car. These devices, known in the art as "mucking machines," are required to operate in very cramped space and are subjected to high loads under adverse conditions, such as shock, dirt, imperfect alignment of supporting structure, etc. Furthermore, such devices are commonly operated by unskilled labor.

It is the principal object of this invention to provide a mucking machine capable of operation in a narrow mine tunnel and requiring a minimum of head room and which incorporates a scoop mounted on a rocker and adapted to engage a muck pile and subsequently swing about the rocker to deposit a load at the rear of the machine.

Another object is to provide a device of this type in which a rocker-supported scoop may be crowded forward, by means of a carrier sliding relative to a stationary base.

Another object is to provide a mucking machine of this type, employing flexible cables, which permit the rocker to move on the carrier, but which prevents sliding motion or lateral turning movement of the rocker and carrier.

A further object is to provide such a mucking machine having means accessible at the rear of the device for shifting a scoop laterally of the mine tunnel for engaging different portions of a buck pile.

Other objects and advantages, it is believed, will be apparent from the following detailed description of a preferred embodiment thereof, as illustrated in the accompanying drawings, in which:

Figure 1 is a side elevation, partly in section, with the scoop in loading position;

Figure 2 is a plan view thereof;

Figure 3 is a side elevation, showing the scoop in discharge position;

Figure 4 is a transverse sectional view, taken substantially on the lines 4—4, as shown in Figure 1;

Figure 5 is a sectional elevation, taken substantially on the lines 5—5, as shown in Figure 1;

Figure 6 is a sectional detail, taken substantially on the lines 6—6, as shown in Figure 1;

Figure 7 is a sectional plan view, partly broken away, showing details of construction of the power unit employed in connection with my invention;

Figure 8 is a fragmentary plan view, partly in section, showing the air valve for the air motor, which may be used to provide power;

Figure 9 is a sectional elevation, taken substantially on the line 9—9, as shown in Figure 3;

Figure 10 is a fragmentary perspective view, showing details of the mechanism employed for swinging the scoop from side to side within the mine tunnel;

Figure 11 is a side elevation, partly in section, showing a modification;

Figure 12 is a transverse sectional elevation, taken substantially on the lines 12—12, as shown in Figure 11; and

Figure 13 is a transverse sectional detail, taken substantially on the lines 13—13, as shown in Figure 11.

Referring to the drawings, a pair of rails 10 and 11 may be mounted on ties 12 within a mine shaft for the primary purpose of providing a track for a mine car 13 (see Figure 3). Transverse supports 14 and 15 are provided at opposite ends of a base 16, which extends longitudinally of the rails 10 and 11. The base 16 is pivotally connected at 17 to the support 14 and is provided with laterally extending projections 18 and 19, which rest on the transverse support 15. The transverse support 15 is formed as an arc of a circle, having the pivot 17 as its center, so that the base 16 may swing from side to side through the angle marked A, as shown in Figure 2, the projections 18 and 19 being slideable over the transverse support 15. The base, generally designated 16, may comprise a single I-beam, which may be cut and rewelded at points along its length to reduce the normal distance between the top and bottom flanges 20.

A carrier 21 is supported on the base for sliding movement longitudinally thereof. A roller 22, mounted on the base 16 at the forward end thereof, provides a bearing between the movable carrier 21 and the relatively stationary base 16. Means are provided for effecting translation of the carrier 21 with respect to the base 16 and, as shown in Figures 1 to 10 of the drawings, this means includes a rotary screw 23 and a cooperating nut 24, which is nonrotatably fixed at the rear end of the carrier 21.

The carrier 21 may include a pair of laterally spaced I-beams 25 and 26, suitably connected at

one end by means of the nut 24 and joined at the other end by any convenient means, not shown. Mounted on the upper surfaces of the I-beams 25 and 26 are a pair of guide flanges 27 and 28. These flanges cooperate with the outwardly extending portions of the upper surfaces of the beams 25 and 26 to define parallel guideways for a rocker assembly, generally designated 29. The rocker assembly 29 includes a pair of curved rockers 30 and 31, adapted to roll along the guideways, designated 32, provided by the beams 25 and 26 and flanges 27 and 28. It will be observed that the members 30 and 31 are not of uniform curvature, but have an increasing radius of curvature toward the forward end of the rocker assembly 29. A tension element 33 rigidly connects the front end of the rocker assembly to the rear end thereof to avoid bending stresses in the rockers 30 and 31 under conditions of use, as will be described more fully hereinafter.

A bucket or scoop 34 is fixed on the forward end of the rockers 30 and 31 and angle braces 35 and 36 are provided as gussets to stiffen the connection therebetween. The scoop 34 has a bottom 7, provided with a forward edge 8, sides 37, a rear face 38, and a dumping shelf 39. Means are provided for preventing relative sliding movement between the rocker assembly 29 and the guideway 32 on the carrier 21 and, as shown in the drawing, this means includes a forward pair of flexible cables 40, having one end thereof secured at 41 to the gussets 35 and 36 and the other end thereof fixed to the carrier 21 at 44. These cables 40 lie under the flanges 42 of the rockers 30 and 31, as shown in Figures 1 and 4. A second set of flexible cables 43 are provided for preventing rearward movement of the rocker assembly 29 on the carrier 21. These cables 43 are fastened to the carrier 21 at 45, near the forward end thereof, and extend beneath the flanges 42 on the rockers 30 and 31 for connection to the rocker assembly 29 at 9.

From the above description, it will be understood that the pairs of cables 40 and 43 permit the rocker assembly 29 to roll on the carrier 21; but prevent sliding movement between the carrier 21 and rocker assembly 29.

It will be observed that, while the major portion of the length of the rockers 30 and 31 is curved, the extreme rearward ends of the rockers are formed with a flat portion 46. This flat portion 46 contacts the guideways 32 at the extreme rearward end of the carrier 21 and causes a bumping of the rocker assembly 29 relative to the carrier 21 and a slight raising of the scoop 34. Figure 3 shows the scoop in such elevated position. Means are provided for moving the rocker assembly 29 from the loading position shown in Figure 1 to the dumping position shown in Figure 3. This means may include a chain 47, which extends under a drive sprocket 48 and has its free end extended over spacers 49 and 50, which join the rockers 30 and 31. The extreme end of the chain 47 is connected to a plate 51, mounted at one end of a cushion 52, the chain extending axially through an opening provided in the cushion. A stop collar 53 is mounted rigidly on the arm 54. The chain 47 extends through an opening in the bumper 55, mounted rigidly on the spacer 50. The arrangement of parts is such that tension applied to the chain 47 first slides the collar 53 into engagement with the bumper stop 55 and thereafter compresses the cushion 52. A rod 56, attached to the arm 54, extends forwardly to operate the latch 57, which is pivotally mounted on

the rod 33, at 58. A stationary member 59, fixed at the forward end of the carrier 21 cooperates with the latch 57 to maintain the rocker assembly 29 in the loading position. Applying tension 5 to the chain 47 first serves to release the latch 57 by moving the arm 54 relative to the member 33. Continued application of tension to the chain 47 brings the collar 53 against the stop 55 and, after some compression of the cushion 52, depending 10 on the load carried by the scoop 34, the rocker assembly 29 rolls on the carrier 21 toward the dumping position shown in Figure 3. A tension spring 60 is provided, which normally maintains the latch 57 in its closed position and holds the end member 51 spaced from the stop element 55.

A mine car, a portion of which is shown diagrammatically in Figure 3 may be moved along the rails 10 and 11 into close proximity to the scoop 34 in its dumping position and the load in 20 the scoop slides along the skirt 39 by gravity and drops into the car 13.

Power means are provided for turning the screw 23 to advance and retract the carrier 21 and for turning the drive sprocket 48 for rolling the rocker assembly 29 on the carrier 21. This power means may include an air motor 61 having opposed inlets 62 and 63 communicating by way of inlet pipes 64 and 65 to a control valve housing 66. The movable valve element 67 may be shifted in 25 the housing 66 to supply air under pressure from the supply line 68 to either of the pipes 64 or 65. Air supplied through the pipe 64 causes the motor 61 to turn in a forward direction, whereas air supplied through the pipe 65 causes reverse rotation 30 of the air motor 61.

A pivotally mounted valve control member 69 is connected by a link 70 to the valve 67. Movement of the control rod 69 toward the left, as shown in Figures 1, 2 and 3, causes forward rotation of the air motor 61, and the extent of movement of the rod 69 determines the passage area available between the supply line 68 and the pipe 64, so that a high speed is obtained by shifting the control rod 69 to the extreme right, 40 while the lower speed is obtained at an intermediate position. Similarly, shifting the control rod 69 to the right causes reverse rotation of the air motor 61, at any desirable speed, depending upon the extent of movement of the valve 67. The rod 69, therefore, controls both the direction and the speed of the air motor 61. The drive shaft 71 of the air motor 61 carries a pinion gear 72, which is adapted to mesh with a ring gear 73 fixed on the stub shaft 74. A screw 23 is in 45 axial alignment with the stub shaft 74 and carries a clutch housing 75 at its extreme end encircling a portion of the stub shaft 74. Friction clutch means, not shown, is provided within the housing 75 and adapted to be actuated by the shifter fork 76 to form a driving connection between the stub shaft 74 and the screw 23. A second clutch housing 77 carrying a sprocket 78 is rotatably mounted on the stub shaft 74 and is adapted to be clutched thereto by means of the 50 friction clutch, not shown, mounted within the housing 77 and actuated by the shifter fork 79. The forks 76 and 79 are pivotally mounted at 76^a and 79^a, respectively. A control bar 80 is secured to the shifter collar 76 so that movement of the lever 80 toward the left serves to engage the clutch 75 to drive the screw 23. The control lever 69 is attached to the shifter fork 79 so that motion of the control lever 69 to the right serves to engage the clutch 77 to turn the drive sprocket 75 55 48. The sprocket 48 is mounted on a shaft 81,

carrying a bevel gear 82, meshing with a pinion 83. The pinion 83 is fixed on a shaft 84 driven by a sprocket 85 fixed thereon. A chain 86 connects the sprocket 78 with the sprocket 85. A spring-biased chain roller 87 is provided for rolling up the chain 47 after it has passed under the drive sprocket 48.

Means are provided for preventing over-travel of the carrier 21, relative to the base 16 and, as shown in the drawings, this means includes an angle bracket 88 fixed on the carrier 21, near the rear end thereof, and having an opening through which a rod 89 passes. One end of the rod 89 carries a bumper block 90 and the other end is connected to a bell crank 91 pivotally mounted on the base 16. A link 92 pivotally connects the bell crank 91 for actuation of the shifter control arm 93. The control arm 93 is rigidly connected to the shifter fork 79.

Another control arm 93^a is pivotally connected to the fork 76 at 94 and carries a bumper block 95 which is engaged by the carrier 21 at the extreme end of its return travel. When the carrier 21 moves to the limit of its stroke to the left, as shown in Figures 1 to 3, the elements 88 and 90 cooperate to actuate the arm 93 and disengage the clutch 77. Similarly, when the carrier 21 moves to the limit of its stroke toward the right, the bumper block 95 causes the arm 93^a to effect disengagement of the clutch 75.

In order to swing the forward end of the base laterally from side to side through the angle A, as shown in Figure 2, a clevis 96 is pivotally connected to one end of the transverse support 14 and a sleeve 97, threaded to the clevis, is pivotally joined with the foot 98 of the shifter rod 99. A stationary pivot 100 connects the shifter rod 99 to a bracket 101, fixed to the base 16 by any convenient means, such as welding.

Operation of the upper end of the shifter rod 99 acts, through the linkage 97 and 98, to swing the base 16 about the pivot 17. The forward end of the base 16 and the scoop 34 therefore may be directed against a muck pile, not shown, in any direction within the limits of the movement.

In operation, the device is installed within a mine tunnel and is clamped to the rails 9 and 10, by any convenient means such as screws 102, provided on the transverse supports 14 and 15. If desired, these transverse supports could be provided with wheels adapted to roll on the rails and having brakes or other stop means to prevent relative motion of the supports to the rails. Air under pressure is supplied to the inlet pipe 68 for supplying power to the motor 61. After a blast in the mine shaft has left a pile of ore or rock in front of the scoop 34, the control lever 80 is moved toward the left to turn the screw 23 from the air motor 61. The carriage 21 and the rocker assembly 29, supported thereby, are then driven forwardly along the relatively stationary base 16 to engage the scoop 34 with the muck pile. The chain 47 unwinds from the spool 87 during this operation.

When the scoop is loaded, the lever 69 is moved to the right to reverse the direction of drive to the screw 23 and to engage the drive to the sprocket 48. Thus, the carriage returns while the sprocket 48 applies tension to the chain 47, thereby disconnecting the latch 57. Continued rotation of the sprocket 48 winds in the chain 47 and causes the assembly 29 to roll on the moving carrier 21, elevating the scoop 34 from the loading position shown in Figure 1 and transferring it to the dumping position shown in Fig-

ure 3. At the end of the motion of the assembly 29 on the carriage 21, the flattened portion 44 of the rockers 30 and 31 cooperates with the guideways 32 to jolt the assembly 29 and thus facilitate the discharge of muck from the scoop 34 into the mine car 13. The carriage completes its return motion just before the scoop discharges. The lever 69 is then automatically returned to its neutral position when the rocker 30 strikes the projecting end 103 of the arm 93, thereby allowing the rocker assembly 29 to return to its loading position under the influence of gravity. The motion of the rocker assembly 21 toward its dumping position is finally arrested through the action of the pairs of flexible cables 40 and 43 and thus a resilient stop is provided which has been found particularly effective for discharging the contents of the scoop 34.

Interlock means are provided for preventing motion of the control lever 69 toward the right while the carrier 21 is in its retracted position, since such action would cause the air motor 61 to turn in a reverse direction and engagement of the clutch 75 would then jam the screw 23 and nut 24. As shown in Figures 3 and 9 of the drawings, this interlock means includes an abutment piece 104 pivotally mounted on the control arm 93 at 105 and is normally adapted to contact the underside of the upper flange on the carrier beam 26, when the carrier 21 is in its retracted position. Until such time as the carrier 21 is moved away from its retracted position by the screw 23, the abutment piece 104 holds the control arm 93 down so that the shifter fork 79 and lever 69 cannot be moved toward the right.

In operation, the carrier beam 26 strikes the pivoted abutment piece 104 as the beam 26 moves toward fully retracted position, thus tilting the abutment piece 104 to the position shown in phantom lines in Figure 3. When the rocker assembly 29 contacts the outer end of the control arm 93, the pivot 105 is depressed to permit the abutment piece to swing to a vertical position, and it does so because its center of gravity is below its pivot of pivotal support. When the rocker assembly 29 returns toward its loading position, the arm 93 rises until the abutment piece 104 contacts the underside of the upper flange on the beam 26. In this way reverse rotation of the air motor 61 is prevented until the carrier 21 has been advanced away from retracted position.

This sequence of operations is repeated until the carrier 21 is operating at the extreme end of its range. The base 16 is then shifted forwardly on the rails 9 and 10, to bring the base closer to the remaining portion of the muck pile. If necessary, additional rail sections are provided to extend the rails 9 and 10.

It will be observed that the initial movement of the scoop 34 is in a vertical direction and therefore packing of the muck pile is avoided when the scoop is moved from its loading position. This is an important feature, since it avoids difficulty in loading the scoop 34 on subsequent loading operations.

The entire device is relatively light in weight and may be operated in narrower mine shafts than has heretofore been possible. Furthermore, the overall head room required is very little more than the height of a man. From the operator's position at the rear of the device, he may control all of the operations of the device

during its normal operating cycle. The operator may therefore remain in a relatively safe position and is not exposed to the hazard of moving rock or ore adjacent the muck pile at the forward end of the device.

In the modified form of my device, shown in Figures 11, 12 and 13, hydraulic means are provided for advancing the carrier and for rolling the rocker assembly. Corresponding parts of the modified form of this device are identified with corresponding numbers with the addition of the suffix *a*. The scoop 34^a on the rocker assembly 29^a lies at the forward end of the carrier 21^a in its loading position. The carrier 21^a includes a piston 110 mounted for action within a stationary cylinder 111, mounted on the base 16^a. Pressure supplied to the right end of the cylinder 111 moves the piston 110 to the right to engage the scoop 34^a with the muck pile, not shown. Another piston 112 cooperating with the cylinder 113, mounted on the carrier 21^a carries a sprocket 114, which is movable longitudinally of the carrier 21^a. Pressure supplied to the right end of the cylinder 113 moves the piston 112 to the left and causes motion of the sprocket 114 to the left. A chain 47^a is fixed to the carrier 21^a at 115 and extends over the sprocket 116 rotatably mounted on the carrier. Movement of the sprocket 114 to the right applies tension to the chain 47^a in a manner that will be readily understood. Tensioning the chain 47^a serves, first, to move the collar 53^a and rod 56^a to disengage the latch 57^a and, thereafter, serves to roll the rocker assembly 29^a in the manner described in connection with Figures 1 to 10, inclusive.

A source of hydraulic pressure is provided at 122 and a control lever 117 is arranged to admit pressure into the cylinder 111, upon motion to the left; and to admit pressure into the cylinder 113, upon motion to the right. A connection between the base 16^a and the carrier 21^a is clearly shown in Figures 12 and 13 and may include roller bearing means 118 and 119 at the forward end of the base 16^a and similar bearing means 120 and 121 at the rearward end of the base 16^a. It will be observed that the cylinder 111 is mounted centrally of the carrier 21^a in a position between the I-beams 25^a and 26^a.

Having fully described my invention, it is to be understood that I do not wish to be limited to the details herein set forth; but my invention is of the full scope of the appended claims.

I claim:

1. In a mucking machine, the combination of a base, a carrier mounted for longitudinal movement on the base, a rocker assembly adapted to roll on the carrier, a scoop on the forward end of the rocker assembly, releasable latch means adapted to maintain the rocker assembly in loading position, power means adapted to move the rocker assembly from loading to dumping position, said power means being effective to release said latch means.

2. In a mucking machine, the combination of a base, a carrier mounted for longitudinal movement on the base and provided with laterally spaced guideways, primary drive means for advancing and retracting the carrier on the base, a rocker assembly including laterally spaced rockers adapted to roll on the carrier guideways and being provided with a scoop at its forward end, secondary drive means for rolling the rocker assembly from a loading position to a dumping position, the secondary drive means including a

tension element secured at the rearward end of the rocker assembly, said primary and secondary drive means being simultaneously operable to retract the carrier and roll the rocker assembly toward dumping position.

3. In a mucking machine, the combination of a base, a carrier mounted for longitudinal movement on the base and provided with laterally spaced parallel guideways, a rocker assembly including laterally spaced rockers adapted to roll on the carrier guideways between a loading position and a dumping position, a scoop on the forward end of the rocker assembly, latch means adjacent the scoop for securing the rocker assembly to the carrier in loading position, means including a flexible tension element connected to the other end of the rocker assembly for moving it to dumping position, and a latch release member extending between the ends of the rockers and operable by the flexible tension element to release the latch means.

4. In a mucking machine, the combination of a base, a carrier mounted for longitudinal movement on the base and provided with laterally spaced parallel guideways, a rocker assembly including laterally spaced rockers adapted to roll on the carrier guideways between a loading position and a dumping position, a scoop on the forward end of the rocker assembly, latch means adjacent the scoop for securing the rocker assembly to the carrier in loading position, resilient means acting to maintain the latch means in operative position, a latch release bar extending from the latch means to a location adjacent the other end of said rocker assembly, and a flexible tension element secured to the latch release bar and adapted to move the rocker assembly to dumping position.

5. In a mucking machine, the combination of a base, the base having longitudinally spaced transversely extending supports, the base also including a single longitudinally extending structural element pivotally attached at one end to one of the supports, the other end of said element resting on the other support and being shiftable laterally in an arc relative thereto, means at the pivoted end of said element for swinging the other end laterally in an arc, a carrier mounted for longitudinal movement on the longitudinal element and provided with laterally spaced parallel longitudinal guideways, a rocker assembly including laterally spaced rockers adapted to roll on the carrier guideways between a loading position and a dumping position, a scoop on the forward end of the rocker assembly, and latch means adjacent the scoop for securing the rocker assembly to the carrier in loading position.

6. In a mucking machine, the combination of a base, the base having longitudinally spaced transversely extending supports, the base also including a single longitudinally extending I beam pivotally attached at its rear end to one of the supports, the other end of said I beam resting on the other support and being shiftable laterally in an arc relative thereto, toggle means at the pivoted end of said I beam for swinging the other end laterally in an arc, rollers carried by the I beam, a carrier supported on the rollers for movement along the I beam and provided with laterally spaced parallel guideways, a rocker assembly adapted to roll on the carrier guideways, and a scoop on the forward end of the rocker assembly.

JAMES K. WILDEN.
